B. C. Converse, Atty.

UNITED STATES PATENT OFFICE.

JOHN F. WEBSTER, OF SPRINGFIELD, OHIO.

ADJUSTING DEVICE FOR TOOLS, &c.

SPECIFICATION forming part of Letters Patent No. 269,754, dated December 26, 1882.

Application filed November 22, 1881. (No model.)

To all whom it may concern:

Be it known that I, JOHN F. WEBSTER, a citizen of the Dominion of Canada, residing at Springfield, in the county of Clarke and State 5 of Ohio, have invented certain new and useful Improvements in Adjusting Devices for Mechanics' Tools, Mathematical and other Instruments; and I do hereby declare the following to be a full, clear, and exact description of 10 the invention, such as will enable others skilled in the art to which it appertains to make and use the same, reference being had to the accompanying drawings, and to letters or figures of reference marked thereon, which form 15 a part of this specification.

My invention relates to an improved adjusting device for calipers, compasses, and similar instruments.

The invention consists of parts and combination of parts, all as will hereinafter be described and claimed.

Referring to the drawings, Figure 1 represents a pair of machinist's calipers. Figs. 2, 3, and 4 are views of inside calipers, the latter 25 view showing the three principal members (inclusive of the adjusting lever) in longitudinal section; and Fig. 5 a side elevation of a pair of compasses.

A represents the devices, each having legs 30 f and f' , secondary part or lever a'' , pivotal nuts d d'' , the screw b'' , and the bolt b''' . The secondary part or lever a'' is preferably provided with a conical journal, c'' , which fits 35 snugly in a correspondingly-shaped bearing, c' , in the leg or primary part f' . The secondary and primary parts are held together by means of a bolt, b''' , which is provided with a screw-threaded end, that is inserted in similar threads in the secondary part or lever a'' , said 40 lever serving as a nut to clamp the parts together. Upon the lever a'' , at any suitable point, is a pivotal nut, d , which corresponds to a similar nut, d'' , attached to arm f'' of leg f . These nuts may be placed upon the same side 45 of lever a'' and arm f'' , or they may be placed on opposite sides—that is to say, on sides which face each other. An adjusting-screw, b'' , is inserted in the nuts and draws lever a'' and arm f'' together or forces them apart, as 50 desired.

In Fig. 3 is shown a pair of inside calipers, having my improved device for adjusting the

primary parts. In this tool, and in the others of this class represented in Figs. 1, 2, 4, and 5, the cone-journal is formed upon the axial end of the lever. It is shown in Figs. 1, 2, and 3 in dotted lines, and more plainly in the sectional view, Fig. 4. This cone may be either formed solid of the same piece with the lever, or it may be made separately and riveted on or otherwise fastened to it. One leg of the calipers or compasses has the conical bearing c' bored through it, as seen in the leg f' , Fig. 4. In inside calipers and compasses this limb is cut off above the joint, as the adjusting-lever a'' stands vertically, for convenience in bringing its pivoted nut d on a line with the nut d'' on the end of part f for the adjusting-screw b'' , which extends through them. In the outside calipers the nut d'' is pivoted on 70 one leg of the tool a little below the joint on the outside edge. This arrangement may also be modified by having the fixed lever or arm f'' extending from leg f in any required direction for the nut d'' . In this form of adjustment the axial head of lever a'' being let into one of the legs of the calipers or compasses, its hole is threaded for the screw b''' , so that it forms one part of the joint, which is not only made stronger, but is much better adapted 75 for ease in working and for adjustment than the ordinary joint. By placing lever a'' upon the outside it serves, as before stated, as a nut for the screw on the pintle or pivot of the primary parts.

I am aware that a secondary leg mounted upon the same pintle as the primary parts, and adjusted by means of a screw-bolt working in a screw-threaded hole in one of the primary parts, and having a swiveled nut upon 90 one end, which, when the parts are adjusted by means of the screw, slides in a groove upon the secondary part, is old. I am also aware that dividers have been provided with pivotal bearings in the legs below the joint, and having a screw provided with right-hand threads at one end for adjusting one leg and a left-hand screw on the other end for adjusting the remaining leg; but this device differs from mine, in that the legs cannot be adjusted independently of the screw.

What I claim as new is—

1. In calipers, dividers, or like devices, the combination, with the primary parts, of a sec-

ondary part having a screw-threaded opening and placed upon the outer side of the primary parts to serve as a nut for the pintle of the device, and an adjusting-screw attached to the 5 secondary and one of the primary parts, for the purpose set forth.

2. In a calipers or like device, the combination, with the primary parts, of a secondary part having a screw-threaded opening and 10 placed upon the outer side of the primary parts to serve as a nut for the screw-threaded pintle of the device, and an adjusting-screw having pivotal bearings attached to the secondary and one of the primary parts, for the 15 purpose set forth.

3. In a calipers, compasses, or like device, the combination, with the primary parts, of a secondary part having a screw-threaded opening and placed upon the outer side of the primary parts to serve as a nut for the screw-threaded 20 pintle of the device, and an adjusting-screw having pivotal bearings attached to the inner side of the secondary and one of the primary parts, for the purpose set forth.

JOHN F. WEBSTER.
